UNITED STATES PATENT OFFICE

MAURITS FRANS VISSER, OF WAGENINGEN, NETHERLANDS

MOLE PLOW

Application filed December 11, 1928, Serial No. 325,236, and in the Netherlands December 17, 1927.

For the purpose of laying drain pipes the ordinary practice is to dig narrow trenches in the land. In loamy or loose subsoils, for instance peat-moor, the drain pipes are sometimes supported by interconnected wooden laths placed on the bottom of the trenches.

Later practice in England and recently also in the Netherlands is to form drain holes in the subsoil by means of an implement known 10 as a "mole drainer". Such drain holes, however, will stand for any length of time only in very strong or stiff clay subsoils.

The drawback of the usual device used for digging trenches, laying the drain pipes therein and thereafter filling in the trenches with the soil previously excavated resides in the heavy cost, so that such device is not economical when the lines of drain pipes are to be spaced a relatively small distance apart. 15 In soft or weak land, for instance in newly reclaimed polders, the digging of trenches offers serious difficulties and it is exactly land of this character which urgently requires underground drainage. Mole drainage of such 20 land is, as a matter of course, quite impossible.

Now, the characteristic feature of my present invention is that the pipes, cables or the like are drawn into a subterranean hole made 25 by means of a mole drainer. In using the device, I may interconnect the pipe sections, or I may support the pipe sections, or the cables, on a base which during the drawing operation takes up the tensile stresses. As to said 30 base, this may either be left in the hole, or it may be removed after the laying of the pipes or the like.

My novel method may, for instance, be effectually performed as follows:

40 In use a mole drainer is placed on two beams or planks across the ditch into which the suction drain pipes are to discharge, or, if the suction drain pipes are to discharge into main drain pipes, the mole drainer is placed over a short length of trench dug for this purpose. Thereafter the nose piece, which is fixed to the extreme end of the knife or coulter and which has for its duty to prepare the hole, is set to the required depth. 45

50 The mole, which is connected to said nose

piece, should have a suitable cross section, for instance, that of an inverted trough. To the mole is secured a thin board or lath having a length of say 10-15 feet, in accordance with the width of the ditch or the length of the trench, this board being set to the required depth on a supporting plank. Said board serves as a base or support, on which the drain pipe sections are placed and brought into alignment. Lateral displacement of the sections on the board should be prevented, for instance, by using pipe sections of special cross sectional form, or by the provision of abutments on, or of a guide groove in the board. Preferably the mole drainer is allowed to travel on boards on the ground.

If, now, the mole drainer is drawn in a forward direction through a distance of say 10-15 feet, either directly or by means of a steel rope, the base board with the drain pipe sections supported thereby is drawn into the hole made by the mole. Thereafter, a second board may be placed on the plank and connected with the one already inserted, whereupon a suitable number of drain pipe sections are placed thereon exactly in alignment with the sections already drawn forward, and so on. Alternatively, a series of base boards may be laid in alignment on the ground rearward of the plank and be connected to one another, so that during the forward travel of this base into the hole the drain pipe sections may be placed thereon in alignment, without substantial interruption.

The depth of the mole below the surface is varied as the mole travels forward, whereby the desired slope of the line of drain pipes is ensured.

In lieu of using, in addition to the nose piece for preparing the hole, a separate mole having a greater cross sectional area, I may employ a nose piece of sufficient cross section to perform the combined functions of the two parts 1 and 4 illustrated.

The device can be used irrespective of the nature of the subsoil, that is to say, also in newly reclaimed polders, in quicksand and in peat-marsh.

If desired, the clearances between the pipe sections may be sealed to prevent quicksand 100

from penetrating into the drain. The interconnected base boards prevent the sections from unequal sinking, whereas the fact that the sections are drawn and not pushed into the hole prevent them from getting laterally out of line.

As no manual labour is required for digging, the novel device is less expensive than known devices, especially in loose soil, in which trenches would have to be very wide.

10 Besides, with the present device the soil is not turned.

It is evident that the device can be employed, irrespective of whether the drain 15 pipes have a circular, or a triangular or any other cross sectional shape and that it is immaterial whether the pipes are of wood or of other suitable material. If the soil is sufficiently strong or stiff the supporting 20 base for the sections may be dispensed with, provided that the sections are interconnected, for instance, by spigot and socket joints.

Again, in order to reduce the effort required, I may first make the hole and there- 25 after, in a second stage of the operation, draw the drain pipe sections thereinto.

If it is not strictly necessary to use boards as a permanent base for the pipe sections in the hole, said boards may at the completion 30 of the laying be retracted from the hole, when the pipes should, of course, be prevented from following. If desired, a steel band may be used for temporarily supporting the pipe sections or the cable during 35 their travel, which band may subsequently be retracted from the hole.

On the drawing, which illustrates my in- 40 vention only by way of example and not of limitation:

Fig. 1 is a general view of the apparatus used, in operation.

Fig. 2 is a side elevational view of the coulter with nose piece and mold, and of two drain pipe sections.

Fig. 3 is a cross sectional view on the line 45 III—III in Fig. 2, on an enlarged scale.

Fig. 4 is a cross sectional view on the line IV—IV in Fig. 2, on an enlarged scale.

The mole plough or mole drainer com- 50 prises the ordinary main parts, such as the nose piece 1 for preparing the hole, the coulter 2 (see also Figs. 2 and 4), the vertically adjustable plough beam 3, the wheels and the adjusting device, which latter, how- 55 ever, is of no importance as far as my pres- ent invention is concerned. The mole 4 at- tached to the nose piece 1 is provided with two laterally spaced, rearwardly extending strips 6 by means of which a board 5 can be 60 secured thereto. On this board are placed the drain pipe sections 7, the ends of which fit loosely together, as shown in Fig. 1. Ac- cording to Fig. 2, however, the sections 8 are interconnected by socket and spigot 65 joints. The hole made by the mole 4 has a

cross section as to permit of the free passage of the board 5 with the pipe sections resting thereon. When operation is started, the plough is placed with its wheels on beams 9 across the ditch 10. The board 5 and also 70 the next one, which is to be connected there- to, are then placed in alignment on a plank 11. The normal talus 12 may be excavated, as shown by line 13, in order to gain place for said plank.

At the extreme forward end of the completed line of pipes a gap is cut down in the land through which access can be got to the mole and the latter may be disconnected 75 from the line.

What I claim is:—

A device of the class described comprising a mole; means for drawing the mole through the earth in advance of a ditch, said mole having strips fixed to its sides, said strips having portions extending rearwardly of the mole; a board fixed between the extended portions for supporting tiles and having a flat bottom for engaging the earth, a plank disposed transversely of the ditch for ini- 80 tially supporting the board fixed between the strips to guide the same into the opening produced by the mole, said plank also serving as a rest for additional boards to be connected with the fixed board as the mole 85 progresses through the earth.

In testimony whereof I affix my signature.
